United States Patent Office.

JOSEPH A. LATHAM, OF NEW HAVEN, CONNECTICUT.

Letters Patent No. 75,981, dated March 24, 1868.

IMPROVEMENT IN GARTERS.

The Schedule referred to in these Letters Patent and making part of the same.

TO ALL WHOM IT MAY CONCERN:

Be it known that I, JOSEPH A. LATHAM, of New Haven, in the county of New Haven, and State of Connecticut, have invented a new Improvement in Garters; and I do hereby declare the following, when taken in connection with the accompanying drawings, and the letters of reference marked thereon, to be a full, clear, and exact description of the same, and which said drawings constitute part of this specification, and represent, in—

Figure 1, a top view, and in

Figure 2 a section on line xx .

This invention relates to an improvement in garters, the object of which is to avoid the cording of the limbs, so as to interfere with the circulation, and consists in the insertion of a metallic or similar spring within the band, and providing the band upon the inner side with several cushions, so as to leave a space between the said cushions, the cushions only touching the limb.

In order to the clear understanding of my invention, I will proceed to fully describe the same as illustrated in the accompanying drawings.

A is the band, which encircles the limb, provided at B with any suitable means of fastening the two ends. Through the said band, or securely attached thereto, so as to become practically a band, I arrange a metallic spring, a , as seen in fig. 2, extending from end to end, or nearly so, of the band, (other material than metal may be used, as whalebone or rattan.) Upon the inner side of the band I arrange cushions C, more or less in number, the said cushions formed from any suitable material, as felt or other thick soft fabric, and so that, while the said cushions bear against the limb, the spring will sustain the band so as not to touch or press upon the limb, thus leaving spaces between the cushions for circulation, and by this means the objection heretofore existing to the use of such articles is entirely overcome.

I do not claim as of my invention a garter provided with a spring arranged longitudinally therein, as such is not new.

Having thus fully described my invention, what I claim as new and useful, and desire to secure by Letters Patent, is—

The herein-described garter, constructed with the spring a , and provided with three or more cushions or pads C, with spaces between them, upon the inside of the band, as an improved article of manufacture.

Witnesses:
